UNITED STATES PATENT OFFICE.

ENOS THOMPSON, OF RADNOR, WEST VIRGINIA.

SPARK EXTINGUISHER.

1,109,486.

Specification of Letters Patent.

Patented Sept. 1, 1914.

Application filed August 16, 1913. Serial No. 785,181.

To all whom it may concern:

Be it known that I, ENOS THOMPSON, a citizen of the United States, residing at Radnor, in the county of Wayne and State of West Virginia, have invented certain new and useful Improvements in Spark-Extinguishers, of which the following is a specification, reference being had therein to the accompanying drawing.

10 This invention relates to spark arresters and has for its object the production of an efficient means for feeding a spray of water to the top of a smoke-stack of a locomotive or other engine for preventing the flying of 15 live sparks from the upper end of the stack.

Another object of the invention is the production of an efficient means for supporting the water supply pipe upon the boiler of the engine in such a manner as to allow ready 20 access to be had thereto.

With the above and other objects in view this invention consists of certain novel combinations, constructions, and arrangements of parts as will be hereinafter fully 25 described and claimed.

In the accompanying drawing:—Figure 1 is a side elevation of a boiler of an engine partly in section. Fig. 2 is a section taken on line 2—2, of Fig. 1. Fig. 3 is an enlarged 30 vertical section through the upper end of the smoke-stack used in connection with the present invention. Fig. 4 is a detail perspective view of the strainer carried by the inlet end of the water supply means for supplying the water to the upper end of the 35 smoke-stack. Fig. 5 is a detail perspective of one of the pipe supporting brackets carried by the boiler. Fig. 6 is a detail perspective of one of the brackets carried by the 40 smoke-stack for supporting the water supply pipe in engagement therewith.

By referring to the drawing it will be seen that 1 designates the boiler and under the rear end thereof is placed the usual fire-box 2. A water supply pipe line 3 passes longitudinally of the boiler and is placed upon one side of the steam dome 4 so as to be out of the way of the steam dome, and this water supply pipe 3 passes through a plurality of brackets 5. These brackets 5 comprise vertically extending portions 6 which are provided with centrally located apertures 7 for allowing the pipe 3 to pass therethrough, and these vertically extending portions 6 of the brackets 5 are supported upon broad base portions 8 through which pass

bolts 9 for anchoring the same and holding the body portion against rotation upon the boiler 1. The pipe supporting members 5 are also provided with depending threaded stems 10 for being threaded into the boiler for constituting an efficient securing means for holding the pipe supporting member in engagement with the boiler.

The water supply pipe 3 carries at its forward end an elbow 11 which supports a vertically extending pipe 12, and this pipe in turn carries an elbow 13 which elbow engages a pipe 14 extending into a smoke-stack 15, and this pipe 14 in turn carries an elbow 16. A pipe 17 is supported by the elbow 16 and this pipe carries the perforated water spray hood 18 hereinafter described. The pipe 12 is supported in engagement with the smoke-stack 15 by means of brackets 19 and these brackets are provided with laterally extending ears 20 for allowing the brackets 19 to be securely in engagement with the smoke-stack by means of bolts 21. The brackets 19 are provided with centrally located apertures 22 for allowing the vertically extending pipe 12 to pass therethrough.

The rear end of the pipe 3 carries a valve 23 which is supported by means of the valve stem and handle 24, and this valve 23 carries a depending pipe 24' which pipe passes through a threaded collar 25 for holding the pipe in the boiler 1. A strainer casing 26 is suspended from the lower end of the pipe 24 and comprises a substantially square body 90 having a collar 27 threaded upon the lower end of the pipe 24' for connecting the strainer 26 thereto. The strainer body 26 is provided with a plurality of perforations 28 as illustrated in Fig. 4 of the drawing. 95 It should be understood that through the medium of the valve 23 the supply of water to the smoke-stack may be increased or decreased at the will of the operator.

The spray hood 18 is positioned near the top of the smoke-stack 15 as illustrated in Fig. 1 and this spray hood comprises a substantially conical body provided with a plurality of apertures 29. A plurality of partitions 30 are carried within the hood 18 and these partitions are also provided with apertures 31 for breaking the water up into fine sprays as the water is discharged through the pipe 17.

The operation of the device is as follows: 110 As the sparks pass from the fire-box the same will pass up through the smoke-stack

15 and the pressure within the boiler 1 will cause the water to be forced up through the pipe 24 through the pipe 3 through the pipe 12 up through the pipes 14 and 17 into the 5 spray hood 18 whereupon the water will be discharged from the top of the smoke-stack in fine sprays and thereby extinguishing any live sparks which would be discharged from the upper end of the smoke-stack.

10 It should be understood as stated above that the supply of water may be regulated by means of the valve 23 according to the amount of cinders and live coals which are being discharged through the smoke-stack

15.

Having thus described the invention what is claimed as new, is:—

10 In a spark arrester of the class described the combination with a boiler, a stack, a supply pipe passing through said boiler, means 20

for controlling the passage through said pipe, a strainer carried by one end of said supply pipe for preventing the admission of solid substance into said supply pipe, of a cone-shaped spray-hood carried by said supply pipe and positioned in the upper end of said stack, said cone-shaped spray-hood provided with perforated side walls, a plurality of perforated partitions carried within said spray-hood for breaking water or liquid passing therethrough into fine spray and for discharging a fine spray from the upper end of said stack thereby increasing the draft through said stack.

25 In testimony whereof I hereunto affix my signature in presence of two witnesses.

30 ENOS THOMPSON.
